US00D428076S

United States Patent [19]

Wise et al.

[11] Patent Number: Des. 428,076

[45] Date of Patent: ** Jul. 11, 2000

[54] TOY CAR

[75] Inventors: **Robert D. Wise; Dorothea A. Wise**,
both of Akron, Ohio[73] Assignee: **Rubbermaid Incorporated**, Wooster,
Ohio

[**] Term: 14 Years

[21] Appl. No.: 29/089,199

[22] Filed: Jun. 9, 1998

[51] LOC (7) Cl. 21-01

[52] U.S. Cl. D21/548

[57] CLAIM

The ornamental design for a toy car, as shown and described.

DESCRIPTION

FIG. 1 is a top left perspective view of a toy car showing our new design; the broken lines showing of tires for a toy car are for illustrative purposes only and form no part of the claimed design;

FIG. 2 is a left side elevational view thereof; the right side elevational view being a mirror image;

FIG. 3 is a top plan view thereof;

FIG. 4 is a bottom plan view thereof;

FIG. 5 is a front elevational view thereof; and,

FIG. 6 is a rear elevational view thereof.

The window areas in FIGS. 1-3 and 5-6 form no part of the claimed design.

1 Claim, 3 Drawing Sheets
